By John Adams
Attorney.

UNITED STATES PATENT OFFICE.

SAMUEL Z. C. WESTERFIELD, OF WASHINGTON, DISTRICT OF COLUMBIA.

DESIGN FOR AN ELECTRIC TABLE LAMP.

Application filed April 24, 1925. Serial No. 13,215. Term of patent 7 years.

To all whom it may concern:

Be it known that I, SAMUEL Z. C. WESTERFIELD, a citizen of the United States, residing at Washington, in the District of Columbia, have invented a new, original, and ornamental Design for Electric Table Lamps, of which the following is a specification, reference being had to the accompanying drawing, forming a part thereof.

The figure is an elevation of my electric table lamp.

In the drawings, 1 represents a helmet; 2 the representation of a cartridge; 3 a forest, which forms the base of the device.

What I claim is:

The ornamental design for an electric table lamp, as shown and described.

SAMUEL Z. C. WESTERFIELD.
